2 SHEETS—SHEET 2.

UNITED STATES PATENT OFFICE.

GEORGE C. KIMMEL AND HERMAN BILLING, OF CINCINNATI, OHIO.

SAFETY ZONE AND MARKER FOR THE SAME.

1,403,033.

Specification of Letters Patent. Patented Jan. 10, 1922.

Application filed April 29, 1920. Serial No. 377,583.

To all whom it may concern:

Be it known that we, GEORGE C. KIMMEL and HERMAN BILLING, citizens of the United States, residing at Cincinnati, in the county 5 of Hamilton and State of Ohio, have jointly invented certain new and useful Improvements in Safety Zones and Markers for the Same, of which the following is a specification.

10 It is the object of our invention to provide new and useful safety zones and markers for the same of permanent character, which are arranged to be imbedded in the street or roadway, so as to become a permanent part 15 of the same; further, to provide safety zone markers which are a permanent part of the street or roadway, and so constructed and arranged that the same are not effaced by travel thereover; further; to provide novel 20 safety zone markers provided with novel means for fixing the same in the street or roadway and with novel means to assure the visibility throughout travel thereover; and, further, to provide a safety zone marker of 25 novel construction and arrangement.

The invention will be further readily understood from the following description and claims, and from the drawings, in which latter:

30 Fig. 1 is a plan view of a section of a street having our invention applied thereto. Fig. 2 is a plan view of one of the blocks of our improved device.

35 Fig. 3 is a central longitudinal vertical section of the same, taken on the line 3—3 of Fig. 2.

Fig. 4 is a plan view of the base of the same.

Fig. 5 is a horizontal section of the same 40 taken in the plane of the line 5—5 of Fig. 6.

Fig. 6 is a side elevation showing abutting blocks and the manner in which the same are imbedded in the roadway.

Fig. 7 is a cross-section of the same taken 45 on the line 7—7 of Fig. 6.

Fig. 8 is a cross-section of portions of the roadway taken on the line 8—8 of Fig. 1, to show the association of our improved device with car-tracks.

50 Fig. 9 is a plan view of a curved base of our improved device, having an insert, partly broken away; and,

Fig. 10 is a horizontal cross-section of the same.

55 Suitable roadways are exemplified at 21,

22, in which our improved device is imbedded. The roadway is exemplified as comprising street car-tracks 24, 25, having rails 26, the arrows showing the directions of travel along the tracks. Our improved device is exemplified as marking off safety zones 27, 28, and safety crossing zones 29, 30, 31 and 32.

Our improved device preferably comprises blocks 35, which preferably comprise 65 a base 36, and an insert 37, the insert forming the marking portion of the device. The base is formed by a suitable traffic-resistant material, for instance cast-iron, and the marking insert is preferably composed of a 70 distinguishing material, which is also traffic-resistant, and may be an alloy, which will have an appearance readily distinguished from the surface of the adjacent roadway. This appearance may be bright or white, or 75 light in color. We prefer to make the distinguishing strip of a white metal alloy, containing for instance aluminum, tin, zinc or other material imparting a distinctive appearance. Preferably the side margins or 80 walls of the base as well as the inserts are of materials contrasting in appearance or color from each other and the surface of the roadway. Travel of auto tires polishes the inserts. 85

We prefer to unite the base and the insert in such a way as to form a firm union between them. The base may, for instance, be first formed and then the insert inserted. We prefer to form the base with a recess 41, 90 extending lengthwise thereof, into which the insert may be poured after the formation of the base. We prefer to provide the base with a lengthwise groove 43, having overhanging side walls 44, into which the material of the insert extends for forming a tongue 45 extending lengthwise of the insert which is located in the lengthwise extending groove in the base for holding the insert downwardly firmly upon the base. We prefer to make this groove contracting in opposite directions toward the ends of the base, as exemplified at 42, the tongue being correspondingly contracting toward its ends. 95

The recess is at each of its sides provided with an upwardly and outwardly sloping wall 48, from which an upright wall 49 of the base extends upwardly, the insert having corresponding reverse walls matching therewith so as to provide a substantial 100 105 110

thickness of material extending up and down between the side edges of the insert and the side walls of the recess, and forming side walls for the insert at the top of the 5 latter.

The construction is such that when the insert is poured into the recess in the base, the metal of the insert will, in shrinking, find relief lengthwise of the base, due to the 10 widening walls of the groove toward the middle of the base, so as to avoid parting or cracking or seaming of the insert when cooling. A firm connection between the insert and the base is provided by providing a flow 15 of metal lengthwise of the recess toward both its ends from the middle of the length of the recess, so as to laterally fill the space between the side walls of the groove and of the recess. Suitable means are provided at the ends of 20 the recess, as by means of dams across the respective ends of the recess, to limit the endwise flow of the metal of the insert. This dam may be so placed and arranged that the metal of the insert, when cast, will extend 25 slightly beyond the ends 51, 52, of the base, the overhanging ends of the insert being trimmed in line with said ends after the same has been cast.

One end of each of the bases is provided 30 with a tongue 54, and the other end with a groove 55, these tongues and grooves being shown extending horizontally across the widths of the blocks. The tongue is preferably of smaller cross-section in height and 35 length than the groove, and the space between the tongue and the walls of the groove is preferably filled by a binder 56, when the markers of our improved device are put in place. This binder may be the material of 40 which the roadway or its foundation is composed, for instance cement or concrete, exemplified at 57, or asphalt, or other material. Binders 58, 59, are located between the rails and the proximate ends of the 45 markers, these binders extending into the grooves or about the tongues at the ends of the markers and into the recess at the sides of the rails to firmly hold the blocks in place.

50 The sides of the base are preferably provided with depressions 61, forming ribs 62, between them. The materials of which the roadway is composed is received in these recesses, so that the material of the roadway, for instance cement or concrete, or 55 other material, forms a union with the marker, in order to hold the same in the roadway.

Our improved markers are so constructed 60 as to readily adapt themselves to curvatures for forming rounded ends or corners for the markings of the safety zones, for instance, as shown by rounded corners 63, 64. Curved blocks 65 are exemplified in Figs. 9 and 10, 65 the parts thereof being indicated by similar

but primed reference numerals. The ribs and the parts thereof are formed, as shown by the ribs 62' and the depressions 61' so that the patterns for molding the same may be readily drawn out of the sand, for instance in the direction of the dotted line 66.

Having thus fully described our invention, what we claim as new, and desire to secure by Letters Patent, is:

1. A safety zone marker comprising a base 75 and an insert at the top of said base, said base provided with connecting means between them, the said connecting means contracting in width towards the ends of said safety zone marker.

2. A safety zone marker comprising a base and an insert at the top of said base having overlapping connecting parts between them at the respective sides of said safety zone marker, and the respective ends 85 of said base between said overlapping connecting parts provided with oppositely formed complementary connecting parts integral with said base to connect the proximate ends of endwise arranged markers.

3. A safety zone marker comprising a base and an insert of distinguishing appearance at the top of said base, the said base provided with a depression extending lengthwise thereof in which said insert is received 95 and the bottom of said insert and the bottom wall of said depression provided with a mating tongue and groove provided with overhanging side walls extending lengthwise of said depression at the respective sides of 100 said safety zone marker, and the respective ends of said base between said overhanging side walls provided with oppositely formed complementary connecting parts integral with said base to connect the proximate ends of 105 endwise arranged markers.

4. A safety zone marker comprising a base the top whereof is provided with a recess extending lengthwise of said marker, and an insert received in said recess, the 110 top of said insert and the tops of the side walls of said recess being at substantially the same level and of contrasting appearances, and the bottom of said insert and the bottom wall of said recess provided with a 115 mating overlapping tongue and groove which contract toward the respective ends of said base.

5. Safety zone markers arranged to be imbedded in a roadway respectively comprising a base, and a part of distinguishing appearance at the top of said base, the ends of said base provided respectively with a tongue, and a groove of greater cross-sectional area than said tongue, the tongues and 125 grooves at the proximate ends of proximate markers arranged end-to-end mating each other with a space between said tongue and the walls of said groove, the sides of said base provided with depressions, and the 130

binding material of the roadway received in said spaces and in said depressions to hold said markers in said roadway.

6. A safety zone comprising straight markers and curved markers, said curved markers forming the roundings in the corners of said safety zone, the proximate ends of said straight markers and of said curved markers provided with complemental tongues and grooves, and inserts in the tops of said respective markers, the said inserts and said straight markers and curved markers pro-

vided with complemental interengaging faces which contract in width towards each of the ends of said respective markers.

In testimony whereof, we have hereunto signed our names in the presence of two subscribing witnesses.

GEORGE C. KIMMEL.
HERMAN BILLING.
